FUEL INJECTION DELIVERY VALVE

Oswald Schlaupitz, Canton, Ohio, assignor to The
Timken Roller Bearing Company, Canton, Ohio,
a corporation of Ohio

Application November 20, 1937, Serial No. 175,548

3 Claims. (Cl. 251—144)

This invention relates to pumps for supplying fuel to the injection nozzles of compression ignition engines, particularly fuel injection pumps of the kind having a pressure operated delivery valve adapted, upon relief of the pressure in the pump cylinder during the working stroke of the piston, to cut off communication between said cylinder and the pressure operated fuel injection nozzle supplied thereby and thus permit said nozzle to close and terminate the injection of fuel into the combustion chamber of the engine. The principal object of the present invention is to devise a simple, economical and compact delivery valve for the above type of fuel injection pump adapted, after cutting off communication between the pump cylinder and the fuel injection nozzle, to relieve the pressure which still exists in the fuel line leading from said cylinder to said nozzle and thus permit said nozzle to close rapidly without leakage or dribble of fuel therefrom into the combustion chamber of the engine. The invention consists in the construction, combinations and arrangements of parts hereinafter described and claimed.

In the accompanying drawing, which forms part of this specification and wherein like symbols refer to like parts wherever they occur,

Fig. 1 is a central longitudinal section through the upper portion of a fuel injection pump provided with a delivery valve embodying my invention; and

Fig. 2 is an enlarged central longitudinal section through said pump in the region of said discharge valve.

In the accompanying drawing, my invention is shown in connection with a pump of the kind used for supplying liquid fuel to the pressure operated fuel injection nozzle of an internal combustion engine of the compression ignition type. The upper portion of the pump body or housing 1 has a vertical bore extending therethrough, in which is mounted a cylinder 2 having an enlarged upper end or head portion 3 that is supported on an annular seat 4 provided therefor in said bore. Mounted for reciprocating movement in the pump cylinder or barrel 2 is a piston 5, which cooperates with said cylinder to form a pressure space or pump chamber 6 therein at the upper end thereof. The pump cylinder 2 has a radial fuel port 7 therein adapted to establish communication between the pump chamber 6 and a fuel chamber or passageway 8 in the pump housing 1. The piston 5 is provided with an annular groove 9 which communicates

with said pump chamber through a longitudinal peripheral groove 10 in said piston.

Mounted in the upper end portion of the cylinder receiving bore of the pump housing 1 is a cylindrical valve seat and supporting block 11 having an outstanding base flange 12 which snugly fits said bore and centers said block therein. The cylindrical valve block 11 extends upwardly into the enlarged lower end portion of the axial bore of an outlet fitting 13 whose lower end portion is threaded into the upper end of the housing bore and bears against a compressible gasket 14 seated on the base flange 12 of said valve block. Secured to the upper end of the outlet fitting 13 by means of a union 15 is a fuel delivery pipe or pressure conduit 16 that leads to a suitable pressure operated fuel injection nozzle (not shown). The cylindrical valve block 11 has a cylindrical bore 17 extending axially therethrough which communicates at its upper end with the axial bore of the outlet fitting 13 and has its lower end portion reduced to form a port 18 that communicates with the upper end of the pump chamber or pressure space 6. The upper end of the port is flared to form a conical valve seat 19; and the wall of the cylindrical bore 17 is provided above said valve seat with an annular groove 20.

Mounted for reciprocating movement in the enlarged portion of the axial bore 17 of the valve block 11 is a cylindrical valve member 21 having a reduced lower end portion 22 that forms an annular abutment surface 23 and is beveled, as at 24, for engagement with the conical valve seat 19 at the upper end of the port in the bottom of said valve block. The valve 21 is provided with an axial bore 26 that leads downwardly from the upper end thereof and terminates short of the reduced lower end of said valve in a reduced lower end portion that is in communication through radial ports 27 with the annular groove 20 in the valve supporting bore 17 of the valve block in all positions of the reciprocating movement of said valve. This reduced lower end portion of the axial bore 26 of the valve 21 forms an annular seat 28 for the lower end of a coil compression spring 29 whose upper end bears against an annular shoulder 30 provided therefor in the upper end portion of the axial bore of the outlet fitting 13.

By the arrangement described, fuel drawn into the pressure space or pump chamber 6 during the suction stroke of the piston 5 is placed under pressure when said piston, during its pressure stroke, passes above the port 7 in the cylinder

2. During this pressure stroke of the piston, the pressure of the fuel on the lower end of the spring loaded valve 21, forces said valve upwardly off its conical seat 19 at the upper end 5 of the port 18 in the bottom of the valve block 11 and exposes the annular abutment surface 23 to the fuel which passes through said port into the lower end of the valve supporting bore of said valve block. The upward movement of 10 the valve continues until the annular abutment surface 23 thereof passes above the lower edge of the annular groove 20 in the valve supporting bore 17 of the valve block. In this position of 15 the valve, the fuel flows around the abutment surface 23 of the valve into the annular groove 20 in the valve supporting bore 17 of the holder, thence through the radial ports 27 in said valve into the axial bore 26 thereof and thence through the outlet fitting 13 and the discharge or pressure conduit 16 to the fuel injection nozzle which 20 is opened by the fuel pressure.

At a predetermined point in the pressure stroke of the piston, the annular groove 9 therein is placed in communication with the port 7 in the cylinder, thereby relieving the pressure in the 25 pump chamber 6 and on the lower end of the delivery valve 21. The valve is forced downwardly by the pressure of the spring 28 and the higher 30 pressure of the fuel in the fuel conduit 16, thereby cutting off communication between said pump chamber and said conduit. During this closing 35 movement of the valve, communication between the pump chamber and the fuel supply conduit is cut off when the annular abutment surface or shoulder 23 of the valve passes below the lower edge of the annular groove 20 in the valve supporting bore 17 of the valve block 11; but the closing movement of the valve continues until 40 the beveled lower end 24 thereof seats against the conical valve seat 19 at the upper end of the port 18 that communicates with the pressure chamber. This continued closing movement of the valve serves to increase the volume of the fuel conduit after communication between the pressure chamber and the fuel discharge conduit is cut off, thereby 45 reducing the pressure of the fuel in said conduit to a pressure that will enable the injection nozzle to close rapidly and without after drip or dribble of the fuel and the objectionable preignition or after burning thereof in the combustion 50 chamber of the engine.

What I claim is:

1. A delivery valve for a fuel injection pump comprising a valve holder having a cylindrical bore extending vertically therethrough, the side wall of said bore being imperforate and the lower end of said bore being an inlet and the upper end an outlet, said bore having an annular groove therein and a conical valve seat below said groove, 55 and a spring loaded cylindrical delivery valve having a snug sliding fit in said bore and having a reduced lower end portion adapted to engage said valve seat and forming an exterior annular abutment surface on said valve above the level 60 of the seat engaging portion thereof adapted during the opening movement of said valve to pass above the level of the lower edge of said annular groove after said valve leaves said conical valve seat and adapted during the closing move- 65

ment of said valve to pass below said level before said valve engages said seat, said valve having an axial bore leading downwardly from the upper end thereof and terminating short of the lower end thereof and radial ports above the level of 5 said exterior annular abutment surface adapted to establish communication between the axial bore in said valve and the annular groove in the axial valve receiving bore of said valve holder in all positions of the sliding movement of said valve. 10

2. A delivery valve for a fuel injection pump comprising a valve holder having a cylindrical bore extending vertically therethrough, the side wall of said bore being imperforate and the lower end of said bore being an inlet and the upper end 15 an outlet, said bore having an annular groove therein and a valve seat below said groove, a delivery valve having a snug sliding fit in said bore and having a reduced lower end portion adapted to engage said valve seat and to form an exterior 20 annular surface on said valve above the level of the valve seat engaging portion thereof, a spring for yieldably holding said valve on said seat, said valve having a bore leading downwardly from the upper end thereof that terminates short 25 of the lower end thereof and is adapted to receive and support the lower end of said spring and radial ports above the level of said exterior annular abutment surface establishing communication between the bore in said valve and the annular groove in the valve receiving bore of said 30 valve holder in all positions of the reciprocating movement of said valve, whereby communication between said inlet and said outlet is cut off when said annular abutment passes below the lower 35 edge of said annular groove and continued closing movement of said valve to engagement with said valve seat relieves the pressure in said outlet. 40

3. A delivery valve for a fuel injection pump comprising a valve holder having a cylindrical 45 bore extending vertically therethrough, the side wall of said bore being imperforate and the lower end of said bore being an inlet and the upper end an outlet, said bore having an annular groove therein and a valve seat below said groove, and a cylindrical delivery valve having a snug sliding fit in said bore and having a reduced lower end portion adapted to engage said valve seat and to form an exterior annular abutment surface on said valve above the level of said valve seat engaging portion, said valve having a passageway 50 therein opening through the upper end thereof into said outlet and through the side of said valve above the level of the exterior annular abutment thereof and establishing communication between said outlet and the annular groove in the valve receiving bore of said valve holder in all 55 positions of the reciprocating movement of said valve, said exterior annular abutment surface of said valve being adapted during the opening movement of said valve to pass above the lower edge of said annular groove after said valve leaves said valve seat and establish communication between said inlet and outlet and adapted during the closing movement of said valve to pass 60 below said lower edge of said annular groove and cut off communication between said inlet and outlet before said valve engages said valve seat. 65
